UNITED STATES PATENT OFFICE.

CHARLES F. PRESCOTT, OF BROOKLYN, NEW YORK, ASSIGNOR TO FRANKLIN RAILWAY SUPPLY COMPANY, A CORPORATION OF DELAWARE.

LATERAL-MOTION DRIVING BOX.

Application filed January 6, 1923. Serial No. 611,910.

My invention relates to lateral motion devices for the driving or axle boxes of locomotives and other railway vehicles, whether associated with pivoted trucks or with other forms of carriage. The invention has the same general objects and purposes as the construction shown in United States Patent No. 1,181,194, issued to Riegel and Woodard on May 2, 1916, (which may be taken 10 as exemplifying the lateral motion appliances in general use), and is intended to meet the same general conditions. While the form of embodiment of my invention here set forth somewhat resembles the construction shown and described in the application of Woodard, Serial No. 422,248, filed in the U. S. Patent Office November 6, 1920, now Patent No. 1,452,862, granted April 24, 1923, and is designed to realize the 15 same general results, the embodiment of my invention here set forth also presents important distinctions and advantages of its own, as will readily be seen hereinafter.

Besides simplicity and relative lightness, 20 economy in construction and installation, easy adaptation to new or old locomotives with minimum change in adjacent parts, and various advantages in action such as keeping the load central on the driving boxes 25 and requiring only one driving box to deflect laterally at a time, my present invention aims to simplify and facilitate manufacture and accurate finishing of important parts; to facilitate adjustment of parts, both 30 for proper and harmonious cooperation in general, and for taking up wear; and to minimize the wear and prolong the useful 35 life of various parts.

How these and other advantages can be 40 realized in a novel manner through my present invention will appear from my description hereinafter of the best embodiment of the invention known to me.

In the drawings, Fig. 1 is a fragmentary 45 side view, partly in section, of a railway vehicle axle and its axle boxes, illustrating the application of my present invention thereto.

Fig. 2 is a corresponding plan view, with 50 certain parts broken away or omitted.

Fig. 3 is a view toward one of the wheels 55 from the inside, with certain parts in section as indicated by the line 3-3 in Fig. 1.

Fig. 4 is a view similar to Fig. 1 illustrating certain modifications.

Fig. 5 is a corresponding view somewhat

similar to Fig. 3, with certain parts in section as indicated by the line 5-5 in Fig. 4.

Referring to Figs. 1, 2 and 3, it will be seen that in the present instance my invention is shown applied to a locomotive in connection with the driving wheels of its "main carriage" (so to term it), rather than with wheels of "accessory carriages" or trucks. The locomotive side frames illustrated are of the standard bar type, with top rails A, bottom rails B, and vertical pedestal jaws C for the vertical movement or play of the driving boxes D. The pedestals C may be provided with the usual shoe and wedge means e and f, or their equivalents, for 60 properly guiding and sustaining the driving or axle boxes D, which rest on the axle G of the driving wheels H. Except as hereinafter described, the parts D, G and H may be of standard or any other suitable type 65 and construction. As shown, the outer and inner flanges i and j of the driving boxes D are spaced apart to afford clearance for 70 such lateral movement of the boxes in the jaws C as is required by the locomotive design and the intended conditions of service, and the outer wear faces of the boxes afford 75 lateral thrust bearing at k for the hubs of the drivers. A due proportion of the load 80 of the vehicle weight, etc., is transmitted to 85 the axle boxes D through the usual spring rigging structure L, and other parts now soon to be described.

In practice, of course, the pedestal jaws 90 C may be closed at the bottom with the usual pedestal frame binder or tie, and the usual lubricating and other accessory parts may be provided: these, however, are all omitted 95 from the drawings, to avoid confusion.

In the present instance, the load is transmitted from each spring rigging structure L to the corresponding driving box D at 100 different points lengthwise of the axle G, through a saddle 15 whose depending leg portions 16, 17 straddle the top rail A and 105 thus bear on the box D at opposite sides of the frame. The clearance between the saddle 15 and the top rail A permits the saddle to ride up and down (relative to the frame) with the movement of the box D due to 110 inequalities of the track, and the flexibility and looseness at joints of the spring rigging permit the saddle to rock slightly. As shown, the outer saddle leg 16 is the longer, and rests or bears directly on the box D, in

a fore and aft seat or socket 18 of appropriate length to take a projection at the lower end of said leg. The shorter inner leg 17 normally bears "solidly" on the box D, as 5 already intimated; but between them extends one end of leverage means 20 pertaining to the lateral motion device. As here shown, the leg 17 rests on the box D only and entirely through the interposed laterally 10 extending arm 21 of the leverage 20. In the present instance, also, the saddle leg 17 has feet 22, 22 separated in correspondence with the diameter of the axle G, and the leverage means 20 comprises a pair of correspondingly located "centering" levers fulcrumed at 23, 23 on brackets 24, 24 projecting inward from the box D. Each saddle foot 22 rests or bears directly in a fore and aft seat or socket 25 in the lever arm 21, of appropriate length to take a projection at the bottom of the foot.

As shown, the levers 20, 20 are fulcrumed in the following manner: that is to say, each bracket 24 has a cylindrically rounded bearing seat 27 in its upper end, extending fore and aft of the locomotive, and each lever 20 has a similar seat 28 in its lower side; and the fulcrum 23, in the form of a cylindrical roller with enlarged heads or shoulders 29 at 15 its ends, lies loose between these seats 27 and 28 with its heads engaged at either side of bracket and lever so as to prevent displacement of these parts fore and aft of the locomotive. The seats 27 and 28 may preferably 20 be of somewhat greater radius than the roller 23, so as to permit some rolling action when the lever 20 rocks, and reduce friction and wear.

It has already been mentioned that one 40 lever arm 21 extends horizontally outward to engage the corresponding saddle foot 22. As shown in Fig. 1, the other lever arm 31 curves and extends downward from the fulcrum 23, still to one side of the axle G, and, indeed, substantially in the same transverse 45 plane as the arm 21. For this depending arm 31 of the lever 20 abutment is provided, to oppose bodily movement of the lever when the box D moves inward under lateral 50 thrust from the corresponding drive wheel H as the locomotive takes a curve with this wheel toward the outside. As shown, such abutment is afforded by a thrust rod member 32 extending from the other side of the 55 vehicle carriage to engage the lower end of the lever arm 31,—which has a hemispherical socket or seat portion 33 for a spherical bearing 34 on the end of the rod 32, with a hole therein to take a pin-like projection 36 60 on the ball 34. This form of interengagement, it will be seen, permits ample angular movement of the parts 20 and 32 relatively to one another under all conditions, yet prevents the rod 32 from dropping out of engagement or chattering injuriously under 65

almost any circumstances. As shown, provision is made for adjusting the abutment by varying the length of the member 32, which to that end is composed of telescoping parts screwed one into the other at 37, with locknuts 38 and convenient hexagonal wrench grips 39.

In Figs. 1, 2 and 3, the construction is all exactly alike at opposite sides of the carriage, and each thrust member 32 is similarly engaged with similar levers 20 at both ends. 75

Fig. 1, especially, shows the normal positions of the parts when the device is properly adjusted and the locomotive is on straight track. The hubs of the wheels H, 80 H abut against the wear faces k, k of the boxes D, D; the arms 21 of all four of the centering levers 20 rest on the boxes; the spring saddles 15, 15 are upright, with both arms bearing solidly on the boxes; all four 85 of the lever arms 31 are practically in working contact with the ball ends 34 of the two thrust members 32; and there are clearances between the outer axle box flanges i at both sides of the carriage on the one hand and the 90 corresponding shoes and wedges e, f on the other hand, while the inner flanges j at both sides are practically in contact or engagement with said shoes and wedges.

If, now, the vehicle takes a curve with the 95 left-hand wheel H at the outside, the resulting lateral thrust on and from this wheel will shift or displace the left-hand box D inward, to the right, carrying the lower ends of the corresponding saddle legs 16, 17, 100 the fulcrum 23, and the two levers 20 as a whole bodily with it. Inward lateral movement of the lower ends of the lever arms 31 being opposed by the abutment or thrust members 32, such movement of the box D 105 and the fulcrum 23 will rock the levers 20 and raise their arms 21 and the inner saddle leg 17 against the load of the vehicle weight,—thus acting to rock the saddle 15 outward, to the left, and lift the load. With proper proportioning of the parts, the inward movement of the saddle legs 16, 17 with the box D, as above described, and the tendency of the top of the saddle 15 to move outward as the saddle rocks will balance or compensate one another,—so that actually the upper part of the saddle that carries the spring rigging will not shift laterally at all 110 with reference to the locomotive side frame, but merely "twist" or tilt to a slight extent, 115 easily permitted by the usual flexibility and looseness of the rigging L. As soon as the vehicle passes from the curve to tangent track and the lateral thrust on the box D is thus relieved, the load acting through the saddle leg 17 will force the arm 21 down again, thus actuating the lever 20 to return the box D to its original position. And when the vehicle takes a reverse curve, a 120 similar action will occur at the other side. 125

130

In the present instance, the normal position of the seats 25 in which the saddle feet 22 rock or turn with reference to the lever arms 21 (during the rocking of levers 20 and saddles 15 as just described) is substantially below the fulcrum 23, so that as the lever arms 21 rise their effective length increases. Owing to this continually increasing leverage of the load of the vehicle weight brought to bear at the left in yielding resistance to the inward displacement of the left-hand box D, under lateral thrust, the thrust of the left-hand levers 20 on the rods 32 will be effective to rock the right-hand levers 20 and raise their arms 21 against the load transmitted thereto by the inner leg 17 of the right-hand saddle 15,—the inner flanges *j* of the right-hand box D continuing to bear against the corresponding shoes and wedges *e*, *f*, so that this box and its fulcrum 23 cannot move. Thus lateral displacement or deflection of either axle box will in effect be divided between the two sides of the carriage; the load of the vehicle weight will be brought to bear at both sides, to oppose a continually increasing resistance to such deflection and to return or recenter the parts at the earliest opportunity; each saddle 15 will be rocked or tilted (and its spring rigging be twisted) only half as much as if the deflection were wholly taken up at one side of the carriage only; and deflection of one box D will entail no deflection whatever of the other. The thrust members 32, it will be seen, serve both as abutments to oppose movement of the levers 20 and as pushrods to transmit such movement of one box to actuate the levers 20 on the other side.

In the main, the construction illustrated in Figs. 4 and 5 is like that of Figs. 1-3, and various corresponding parts and features have therefore been marked with the same reference characters in both cases, as a means of dispensing with merely repetitive description.

Referring, then, to the differences, it will be observed that while one side of the Fig. 4 and 5 construction (in the present instance, the left-hand side) is the same as in Figs. 1-3 up to the top of the saddle 15', the other side wholly lacks any real counterpart for the leverage means 20 and their fulcrum brackets 24. In appearance, indeed, these parts 20, 24 are here replaced by angular bracket-like parts 40 bearing against the inner side of the corresponding (right-hand) axle box D' and resting on its upper surface. But although these parts 40 have seats or sockets 25' for the projections on the saddle feet 22, and hemispherical sockets or seats 33' for the corresponding ball ends 34 of the thrust rods 32, etc., they are functionally mere adjuncts or immobile parts of the corresponding box D',—manu-

factured separate merely for convenience and economy, and in order to allow the box D' and the corresponding saddle 15' to be practically made from the same patterns, etc., as those at the left.

In this case, therefore, instead of lateral deflection of each box D, D' being taken up at both sides of the carriage, as in Figs. 1-3, deflection of either box is taken up at the one side provided with the centering levers 20, etc. When the left-hand box D (that has the levers 20) deflects inward to the right, the action is the same as in the construction of Figs. 1-3, except that the thrust of these levers 20 produces no corresponding effect at the right-hand side of the carriage. In this case, therefore, the thrust members 32 function as absolutely unyielding abutments and the load is raised twice as much at the left as with a similarly proportioned construction of the Fig. 1-3 type under the same conditions. When, on the other hand, the right-hand box D' deflects inward to the left, no rocking or lifting effect whatever occurs at that side; on the contrary, box D', its saddle 15', parts 40, and thrust rods 32 all move bodily to the left the full amount of the deflection, and the levers 20 and saddle 15' at the left are rocked and raised exactly the same amount as for a like inward deflection of the left-hand box D,—i. e., twice as much as would occur at either side for a like deflection in the case of a similarly proportioned Fig. 1-3 construction. In this case, the thrust members 32 still oppose the deflection; but as mere pushrods transmitting thrust and movement to actuate the levers 20, 20 on the other side,—not as effectually resistant abutments at all.

Since the right-hand saddle 15' of Figs. 4 and 5 moves bodily the same amount as its box D' it is desirable to provide for this movement to take place without a corresponding deflection or distortion of the spring rigging structure L. As shown, bearing for relative movement between saddle 15' and rigging structure L is provided, in the form of a fore and aft roller device 41 interposed between the top of the saddle 15' and a superjacent part 42 attached or keyed to the structure L, and provided with depending guide and housing flanges 43 slidably engaged at either side of the saddle 15'. In the present instance, like parts 41, 42 are also provided at the left-hand saddle 15'. The two spring bearings 42, 42 are connected together by a bar 44 shown as cast or forged integral with them, and provided with depending brackets 45 for engaging the inner sides of the frame rails A, A through openings in the inner saddle legs 17, 17, so as to prevent the saddles 15' from exerting any stress on the spring rigging structure L, L. In this case, the left-hand roller bearing 41 also obviates any influence

on the corresponding structure L from the rocking or tipping of its saddle 15'. It will be seen that in the constructions shown in Figs. 1-5, the more important bearing and wearing surfaces (e. g., those for the fulcrum rollers 23) are "in open planes", so to speak, so that they can be easily and accurately machined and finished. All the parts rest freely on one another (including the levers 20 on the fulcrums 23), and can be easily and quickly assembled or taken apart. The levers 20, 20 for each axle box D being entirely separate, and co-acting with separate thrust members 32, 32, minor inaccuracies or differences are of less importance,—since they can easily be compensated by appropriate independent adjustments of the members 32, 32. Proper adjustment of these members 32, 32 to divide and distribute the thrust equally as between the sides of the axle G, etc., is easily made by first shortening them till their ends are loose enough to "rattle" when they are lifted and released, and seeing that the ends of all the lever arms 21 actually bear solidly on the boxes D; then lengthening or "expanding" the rods 32, 32 till all looseness or backlash is just fully taken up,—as can easily be determined, by an experienced workman, from the "solid" resistance suddenly making it impossible to expand a rod any further with a short wrench. Looseness due to wear of any of the parts can be detected and compensated for (by separate expansion of the rods 32, 32) in the same way.

I claim:—

1. A railway vehicle lateral motion device comprising an axle box, means for transmitting the load to the latter, and means at the sides of the axle for yieldingly resisting lateral movement of the box relatively adjustable to equalize their resistance to such movement.
2. A railway vehicle lateral motion device comprising an axle box, means for transmitting the load to the latter, and means at the sides of the axle for resisting movement of the box under lateral thrust separately adjustable to distribute such thrust between said sides of said axle.
3. A railway vehicle lateral motion device comprising an axle box, and separate leverage means at the sides of the axle for independently bringing the load of the vehicle weight to bear in resistance to lateral movement of the box.
4. A railway vehicle lateral motion device comprising an axle box, means for transmitting the load to the latter, and separate leverage means at the sides of the axle interposed between box and load transmitting means, and independently resisting lateral movement of the box.
5. A railway vehicle lateral motion device comprising an axle box, means for

transmitting the load thereto, and means at the sides of the axle, interposed between box and load transmitting means, for bringing the load on the latter to bear in yielding resistance to movement of the box under lateral thrust, relatively adjustable to distribute such thrust between said sides of said axle.

6. A railway vehicle lateral motion device comprising an axle box, separate levers fulcrumed on said box at the sides of the axle for bringing the load of the vehicle weight to bear in resistance to lateral movement of the box, and abutment means for rocking such levers against such load.

7. A railway vehicle lateral motion device comprising an axle box, separate levers fulcrumed on said box at the sides of the axle for bringing the load of the vehicle weight to bear in yielding resistance to movement of the box under lateral thrust, and abutment means for said levers separately adjustable to distribute such thrust between them.

8. A railway vehicle lateral motion device comprising an axle box, separate levers fulcrumed on said box at the sides of the axle for bringing the load of the vehicle weight to bear in yielding resistance to movement of the box under lateral thrust, and thrust members extending from the other side of the vehicle carriage to said levers for rocking them on their fulcrums and thereby lifting the load aforesaid.

9. A railway vehicle lateral motion device comprising an axle box, means for transmitting the load to the latter, separate levers at the sides of the axle fulcrumed on the box with ends interposed between the latter and said load transmitting means, and means for opposing movement of the other ends of such levers, so that lateral movement of the box will rock such levers against the resistance of the load on such load transmitting means.

10. A railway vehicle lateral motion device comprising an axle box, load transmitting means with portions for transmitting load to the box at different points lengthwise of the axle, and separate, independently acting means at the sides of the axle interposed between one of such portions and the box for raising said portion and rocking said load transmitting means on the other such portion when the box is deflected by lateral thrust, and returning the box, under actuation by the portion so raised, when such thrust is relieved.

11. A railway vehicle lateral motion device comprising an axle box, means for transmitting the load of the vehicle weight to the latter, leverage means fulcrumed on said box for bringing such load to bear in yielding resistance to movement of the box under lateral thrust, and adjustable abutment means for said leverage means.

12. A railway vehicle lateral motion device comprising an axle box, means for transmitting the load of the vehicle weight to the latter, leverage means fulcrumed on said box for bringing such load to bear in yielding resistance to movement of the box under lateral thrust, and a thrust member extending from the other side of the vehicle carriage to said leverage means, for rocking the latter and thereby lifting the load aforesaid, adjustable in length to compensate for wear. 45
13. A railway vehicle lateral motion device comprising an axle box, a saddle straddling the frame above the axle box with legs for transmitting the load to the latter at opposite sides of the frame, separate levers fulcrumed on the box at the sides of the axle, with arms operatively interposed between saddle and box, and thrust means extending from the other side of the carriage to said levers for rocking them to bring the load of the vehicle weight to bear in resistance to lateral movement of the box. 50
14. A railway vehicle lateral motion device comprising axle boxes, and means for bringing the load on one of said axle boxes to bear in resistance to lateral movement of the other irrespective of movement of the first-mentioned box. 55
15. A railway vehicle lateral motion device comprising separately movable axle boxes, and means for bringing the load on one of said axle boxes to bear in resistance to lateral movement of the other. 60
16. A railway vehicle lateral motion device comprising axle boxes, means for transmitting the load to one of said boxes, means interposed between said box and load-transmitting means for bringing the load on 65
- the latter to bear in resistance to lateral movement of said box, and means for actuating said latter means to bring such load to bear in resistance to lateral movement of the other box. 70
17. A railway vehicle lateral motion device comprising axle boxes, leverage means fulcrumed on one of said boxes, and means actuated by lateral movement of the other box for rocking said leverage means to bring the load of the vehicle weight to bear in resistance to such movement. 75
18. A railway vehicle lateral motion device comprising axle boxes, means for transmitting the load of the vehicle weight to one of said boxes, a lever fulcrumed on said latter box, with an arm interposed between said box and said transmitting means bearing against the latter at a point normally below the fulcrum, and means actuated by lateral movement of the other box for rocking said lever to bring the load on said transmitting means to bear in resistance to such movement. 80
19. A railway vehicle lateral motion device comprising axle boxes, a saddle straddling the frame above one of said axle boxes with legs for transmitting load to the latter at opposite sides of the frame, a lever fulcrumed on said latter box at its inner side, with an arm extending beneath and bearing against the inner saddle leg, and a thrust member extending from the other axle box to said lever for rocking it to bring the load on said saddle to bear in resistance to lateral movement of said latter box. 85

In testimony whereof, I have hereunto signed my name.

CHARLES F. PRESCOTT.
